ABSTRACT

A die nib is determined by a mathematically defined segment-shaped portion or die nib segment, a multiplicity of which are assembled together to form the die nib proper, each segment contacting its adjoining segment along a mathematically determined curvilinear transverse face whereby work stresses control the distribution of cohesive pressures along the interfaces of the segments, the segment-shaped portions having workpiece engaging walls forming a die opening of the shape desired for shaping the work material, the curvilinear transverse faces being illustrated by a wide variety of forms.

PAIRS OF VALUES FOR n AND K CORRESPONDING TO GIVEN θ MAX AND ALPHA:				
$n = \frac{1-2\theta \max(\tan \alpha) - \sqrt{1-4\theta \max(\tan \alpha) - 4(\theta \max)^2}}{2(\theta \max)^2}$				
$K = (n \cot \alpha)^{\frac{1}{n}}$				
OUTLINED ----- RED IS THE RANGE OF VALUES				
FOR $T=1$ $S = \frac{\pi}{2}$				
OUTLINED ----- YELLOW IS THE RANGE OF VALUES				
FOR $T=1$ $S = \frac{\pi}{3}$				
OUTLINED ----- PURPLE IS THE RANGE OF VALUES				
FOR $T=0.5$ $S = \frac{\pi}{3}$				
OUTLINED ----- BROWN IS THE RANGE OF VALUES				
FOR $T=0.5$ $S = \frac{\pi}{4}$				
REFER TO EQUATION 27 $\tan \alpha = \frac{n \cot S}{(T+1)^n - 1}$

SEGMENTAL DIES

This is a continuation of application Ser. No. 722,778 and filed Apr. 19, 1968, now abandoned.

This invention relates to segmental dies having properties of withstanding stresses that normally cause early failure in such dies of prior art structure (resulting in chipping, cracking, cupping, explosion, etc.), to methods of producing such dies, and to methods of using such dies.

A large variety of dies have been used in the prior art for carrying on die controlled operations, including such working as extrusion (in its various forms, such as forward, backward, impact, reduction, etc.), drawing, upsetting, trimming, punching, shearing, and other operations in fashioning metals. But such prior art dies and operations with them have been far from satisfactory due not only to defects in the products obtained but also because of the relatively short life of the dies employed and their functional costs. In prior art segmental dies, the transversal side walls of the segments that are held in assembled relation to form the complete die nib are flat planar faces that are associated together in such a way that the angle which they make with the plane passing through the central axis of the die opening and the line which the planar segmental faces form along the inner face of the die opening are incompatible with the ability of the segments to adhere together and to prolong the life of the die. Joints that are produced from such contacting planar faces, regardless of their size or peripheral form, are the sources of the problems that arise to militate against the long life and utility of such die segments and dies assembled therefrom in accurately assembled position. As a result, relatively rapid deterioration and inability to avoid or withstand chipping, cracking, cupping, explosion, etc., result.

Among the objects and advantages of this invention are included dies of novel structure and configuration having properties of withstanding maximum work stresses under optimum conditions arising in forming and shaping operations in working a material capable of being used for such purposes. Other objects include the products produced which under these controlled conditions have novel properties, and methods of carrying out these operations, both of production and utilization.

Other objects will appear also, it being understood that various changes may be made in this invention by those skilled in the art without departing from the scope and spirit of this disclosure.

In connection with the following disclosure:

FIG. 1A is a top sectional view of a segmental die of the present invention with the shrink ring or other suitable housing removed and the segments of the die nib in their normal operative position forming a complete die nib and having in horizontal cross-section a central curvilinear die opening.

FIG. 1B is a three-dimensional representation of a segment of a die nib whose top sectional view is given by FIG. 1A.

FIG. 2A is similar to FIG. 1A, the die opening being polygonal.

FIG. 2B is similar to FIG. 1B, the inner face wall of the segment being planar.

FIG. 2C is a portion of a top sectional view of a segmental die nib, the segmental curves being of heterogeneous nature.

FIG. 3 is a portion of a top sectional view of a segmental die nib, the segmental curves C_c being curves of equal pressure.

FIGS. 4 and 5 represent particular cases of the cross-sectional segmental curves illustrated in FIG. 3.

FIG. 6 is a portion of a top sectional view of a segmental die nib in which segmental curves from Classes I, II, and III, all starting with the same initial angle Alpha, are illustrated simultaneously for comparison.

FIG. 7 is a portion of a top sectional view of a segmental die nib with curvilinear central die opening and straight line segmental curves.

FIG. 8 is similar to FIG. 7, the die opening being hexagonal.

FIG. 9 is similar to FIG. 8, the die opening being decagonal.

FIG. 10 is a top sectional view of a segmental die nib in which the die opening is square, and a variety of segments with straight line interfaces are illustrated for comparison.

FIG. 11 is similar to FIG. 10, the die opening being triangular.

FIG. 12 is a top sectional view of a segmental die nib showing one segmental curve of Class II.

FIG. 13 is a top sectional view of a segmental die nib with a hexagonal die opening whose original vertices are faceted, and with Class II segmental curves.

FIG. 14 is a top sectional view of a segmental die nib with a round die opening and reflected curvilinear segmental curves.

FIG. 14A is similar to FIG. 14, the die opening being square.

FIG. 14B illustrates mathematically derived reflection about line D-D' of a segmental curve of FIG. 6.

FIGS. 15 to 19 are mathematically graphed curves of Class III illustrative of intersegmental sides in cross-section of the segments that may be used to contact one another in constructing the segmental die of this invention.

FIGS. 20 through 27 represent graphs mathematically determined by equations 27, 28, 29 and 30 leading to values of the breadth of the die nib wall as described herein below in the specification of the family of Class III segmental die nibs.

FIGS. 28 to 31 are top sectional view of segmental die nibs, representing still further variations in segmental dies mathematically determined in accordance with the present invention.

FIG. 32 represents a vertical central section through a complete die structure, including shrink ring and die holder, for making ball joint studs.

FIG. 32A is a plan view of the die structure shown in FIG. 32.

FIGS. 33, 34, and 35 are mathematically graphed top plan views of the segmental die nibs that are employed in Examples 2, 3, and 4.

FIGS. 36 and 36A are charts giving paired values for n and K corresponding to given values of θ_{max} and Alpha.

The present invention, accordingly, is directed to segmental dies capable of withstanding maximum work stresses under optimum conditions arising in forming and shaping operations in working a material capable of being used for such purposes. Stated generally, the

die employed is a segmental die of mathematically determined geometric structure, namely, a die in which a group of mathematically determined segment-shaped portions may be joined together to form the die nib desired, and the segment portions then held in position to constitute the die proper. Any appropriate structure and method employed in the art for holding die segments together in operative position may be used. They are not the invention here, except insofar as they may cooperate with the die segments to hold the latter in finished die structural form.

The basic feature of the invention here lies in the mathematically determined segment-shaped portion of die nib segment, a multiplicity of which are assembled together to form the die nib proper. Each segment successively contacts its adjoining segment along a mathematically determined curvilinear transversal face. What constitutes the primary advance in the invention set forth here is this mathematically determined geometric structural contact between the segments which accommodates given work stresses by controlling the distribution of cohesive pressures along the interfaces of the segments. In addition, the segment-shaped portions have workpiece engaging walls forming a die opening of the shape desired for shaping the work material.

These curvilinear transversal faces will be illustrated by a wide variety of forms which may be classed in particular groups depending upon the nature of the cohesive pressures which the segments exhibit between one another under given work stresses. The character of these cohesive forces may be produced in widely variant forms of die nib segments and the association of those segments and will be explained in detail below to illustrate how they may vary.

FIGS. 1A, 1B, 2A, and 2B are representative of a theoretically infinite class of die nibs which differ from one another (a) in the angle Alpha the segmental curves C begin at (which can theoretically vary from more than 0° to less than 90°); (b) in the breadth, t , of the die nib wall, which, as will be seen, is subject to particular limitations in certain cases; (c) in the form of the curves C; (d) in the number of segments m , which form the die nib, and (e) in the shape of the die opening, which may be of any curvilinear or polygonal horizontal cross-section.

According to this invention, the segmental curves are so designed that the distribution of the cohesive pressures of the segments against each other may be controlled as desired:

I. These cohesive pressures may be substantially equal along the entire length of the transversal interfaces of the segments, when the work stresses are radiated out substantially equally from the central axis of the die opening.

II. These cohesive pressures may be greater toward the die opening than toward the periphery of the die nib, under similar conditions; or they may be equalized to greater or lesser extent along the transversal interfaces of the segments, when the work stresses are radiated out with less force toward the inner face vertices of the segments than toward points farther along the interfaces of the segments.

III. These cohesive pressures may increase over a certain initial range of the interfaces of the segments, when the work stresses are radiated out substantially equally from the central axis of the die opening; or they

may be equalized to a greater or lesser extent along the transversal interfaces of the segments, when the work stresses are radiated out with greater force toward the inner face vertices of the segments than toward points farther along the interfaces of the segments.

Furthermore, one can obtain heterogeneous segmental curves by plotting them over a certain initial range according to one of the above classes of curves, continuing them over a subsequent range according to another of the above classes, and so on. In this way, the variation in cohesive forces between two points along the interface of the die nib segments can be controlled, within certain prescribed limits, in any direction one wants (see FIG. 2C).

All in sections of this application, some important considerations about the angle Alpha is segmental die design will be given as well as, some important considerations about the choice of the number of segments, m , in segmental die design will be given and, sample cases of die operations and methods of designing the appropriate segmental die for them, utilizing the criteria in this application, will be shown.

Considering the structure of FIG. 1A, this represents a top plan view of a segmental die nib of the present invention without the shrink ring or other suitable housing but with the segments of the die nib in their normal operative position forming a given die opening, which for purposes of illustration is here drawn as circular. In this form the die nib 1 is composed of a given number of segments 2 (here drawn as four) that are associated together to form the die nib 1. For this purpose, each segment 2 has four sides or lateral walls, two of which, marked generally C in horizontal cross-section, are curvilinear, including particular straight line cases, one wall 3 being convex or planar and the other one 4 being concave or planar (see FIG. 1B). The faces of the walls 3 and 4 are made to fit each other, and when joined together in this way the total number of segments will form a complete die nib. As illustrated herein, these curvilinear transversal walls 3 and 4 are desirably determined mathematically as explained in the text (see Examples 1 through 4 of Section VI, as well as appropriate portions of the text).

In addition, each segment has an inner wall 5 which is of curvilinear wall shape, illustrated here as a quarter-circle in horizontal cross-section so that four such inner walls in this case will form the die opening 6, which in this figure is circular in horizontal cross-section. This die opening serves to shape the work material during the work-forming operation, and may have the conventional accommodation of lead angle and finish.

The fourth side wall of each segment may take a predetermined size and shape limited by considerations set forth herein and by the shrink ring or other holding device, and constitutes, in conjunction with the other segments, the outer wall of the complete die nib which is received by the shrink ring or other holding device, for which purpose the ring or holding device should be complementary in size and shape. The shrink ring or holding device may be of conventional design or of special structure.

The top and bottom walls of the segments are desirably smooth but may take any surface finish. In addition, a backing plate or other suitable device may be included in the housing of the die nib.

FIGS. 2A and 2B are similar to FIGS. 1A and 1B respectively, except that the inner wall 5 of each segment in FIGS. 2A and 2B is shaped so that the die opening 6 is polygonal in horizontal cross-section, in this instance hexagonal. Here, too, the dimensions and configuration for the die nib segments are determined mathematically, as illustrated herein.

Once the design for the segments of the die nib has been mathematically determined in accordance with the criteria of this application, the segments may be fashioned by a variety of techniques. Any appropriate fashioning operation available in the art may be used, including powder metallurgy methods, machining, impact extrusion, electrodeposition, and so forth. The segments may be made out of materials which have been used in the prior art, also including plastics, metallo-plastics, powder metals, and metallic structural die materials. The novelty of the design of the segments of the die nib may permit the use of materials and methods in making these segments not conventionally employed in the prior art.

The finished segments thus obtained are assembled as a complete die nib by any satisfactory means. An appropriately designed and finished shrink ring may be heated to a predetermined expanded opening, placed around the assembled segmental die nib, and allowed to shrink as prescribed around the nib by cooling. Any other satisfactory housing may be appropriately fitted about the assembled segmental die nib. The total assembly is critically finished to the necessary dimensions. It may then be used as is, in the working machine holder, or it may be set permanently in its own casing and then placed in the working machine, or it may be held by any other satisfactory means.

I. In segmental curves of Class I above, it is desired to have the pressure of cohesion between adjacent segments of the die nib substantially equal along the entire intersegmental curve, when the work stresses are radiated out substantially equally from the central axis of the die opening. This type of curve may be called a curve of equal pressure and denoted C_c in horizontal cross-section, as represented in FIGS. 3, 4, 5, 6, and 32. It will be shown mathematically that C_c must be a member of a family of circles, and that for each choice of Alpha (the angle at which the curves C_c start from the inner face of the die opening) there is one and only one such circle.

The mathematical equation for the curve C_c is based on the following assumptions:

a. The cross-sectional work stresses are radiated equally in all directions against the inner face of the die nib (in practice, certain work materials are of non-uniform physicals, but their work stresses under given conditions radiate out sufficiently equally to justify this assumption); for round die openings this applies to all forms of operations of extrusion, punching, trimming, shearing, and the like; for polygonal die openings extrusion is an exception.

b. The pressure against a unit arc length is proportional to the product of the inverse of the radius distance from the center of the die opening to the point under consideration, and of Sin Beta (where Beta is the angle formed by the radial line of force, and the tangent to the curve at the point under consideration, r, θ , as in FIG. 3): $1/r \sin \beta$. It is proportional to $1/r$ because the total force gets distributed over larger regions as it moves outward, and to Sin Beta because it is by that

factor that the pressure is multiplied in order to get its component normal to the curve.

The curve C_c in FIG. 3 is represented in polar coordinates by the generic equation:

5 Equation 1

$$r=f(\theta).$$

Since, as stated above, the pressure is proportional to the inverse of the radius times Sin Beta, one can the 10 write the following equation:

Equation 2

$$P=H(\sin \beta/r) \text{ or } P=H[\sin \beta/f(\theta)],$$

15 where H is the factor of proportionality experimentally determined. As will be seen, the formula for the segmental curve $r=f(\theta)$ will be derived without having to establish the value for H .

According to a standard mathematical formula:

Equation 3

$$\cot \beta=f'(\theta)/f(\theta)$$

whence

Equation 4

$$\sin \beta=f(\theta)/\sqrt{f'(\theta)^2+f(\theta)^2}$$

Substituting Equation 4 in Equation 2 above, we have:

Equation 5

$$P=H/\sqrt{(f'(\theta))^2+(f(\theta))^2}$$

In order for this pressure P to be independent of position on the curve, P should then be independent of θ . Thus one gets the differential equation:

Equation 6

$$(f'(\theta))^2+(f(\theta))^2=c^2,$$

where c^2 is some positive constant.

The mathematical solution of this differential equation is:

Equation 7

$$f(\theta)=c \sin(\theta+\alpha)=r,$$

where α is the initial angle the curve makes with the horizontal (see FIGS. 3 and 4), and where c is subject to the condition:

Equation 8

$f(\theta)=1$, or by Equation 7: $c \sin \alpha=1$, in order to have the curve C_c start $r=1$ unit to the right of the center (see FIGS. 3 and 4).

The above Equation 7, $r=c \sin(\theta+\alpha)$, has (in view of 8) as its rectangular equation:

Equation 9

$$(x-\frac{1}{2})^2+(y-[c \sin(\theta+\alpha)/2])^2=(c \sin \alpha)^2$$

where $c=1/\sin \alpha$, or $c=c \sin \alpha$.

Equation 9 represents a family of circles whose center is located at $(\frac{1}{2}, c \sin \alpha)$, and whose radius is $c \sin \alpha$. Thus it is evident that the center of these circular curves is always located on the line $x=\frac{1}{2}$ which passes midway between the center and periphery of the die opening (see FIGS. 3 and 4).

To set up the curve C_c geometrically (see FIG. 4), the die opening is drawn (represented by a circle in FIG. 4); arbitrarily, the distance from the center to the circumference of the opening, or its radius, is considered as one unit. Mark on the circumference the 60° point

Q, and drawn a vertical line ($x=\frac{1}{2}$) through Q. On this line, the center R of the circular curve C_c is located. (More detailed description of the character of the curve is given below.) Let the curve be drawn with R as the center and the distance from R to (1,0) as the radius= $\text{Csc Alpha}/2$. The angle Alpha and the ordinate of R, $\text{Cot Alpha}/2$, are mutually dependent.

In the above Equation 9, the angle Alpha can be chosen from above 0° to below 90° , depending upon the requirements for cohesive pressures and the size of the die. When Alpha is very small, the circular curves C_c approach radial straight lines, and then the cohesive pressure becomes very small (varying with Sin Alpha), and in that case the segments will tend to separate under work pressure; however, the inner corners will be less frangible, and the breadth t of the die nib wall can be relatively large compared with the die opening. The maximum breadth T_{max} of the die nib wall corresponding to this class of curve is derived by maximizing r in the polar Equation 7, $r=c \text{ Sin}(\theta+\text{Alpha})$, and subtracting from it the unit radius of the inner die opening: $T_{max}=r_{max}-1$.

(a) $dr/d\theta=c (\text{Cos Alpha})(\text{Cos } \theta)-c (\text{Sin Alpha}) (\text{Sin } \theta)$.

(b) To determine the maximum r , set $c (\text{Cos Alpha})(\text{Cos } \theta_{max})-c (\text{Sin Alpha}) (\text{Sin } \theta_{max})=0$.

(c) $\therefore \text{Cot } \theta_{max}=\text{Tan Alpha}$, or $\theta_{max}+\text{Alpha}=90^\circ$.

(d) Substituting in Equation 7:

$$r_{max}-c \text{ Sin}(90-\text{Alpha}+\text{Alpha})-c \text{ Sin } 90=c.$$

(e) By Equation 8:

$$(c \text{ Sin Alpha})=1 \text{ or } c=\text{Csc Alpha}.$$

Equation 10 $\therefore T_{max}=c-1=\text{Csc Alpha}-1$.

As Alpha approaches zero, it is thus seen that T_{max} approaches infinity.

Conversely, when Alpha is large, the cohesive pressure between the die nib segments will be great. At the maximum Alpha, the cohesive pressure approaches what it would be if the die were constructed of concentric laminae. In that case the segments will tend to cohere together very strongly, and this cohesive pressure will increase with increase of internal work pressure. And since there will be no separation of the segments, leakage into spaces between segments is completely eliminated. However, the inner corners of the segments here will be more pointed and therefore more apt to chip than when Alpha is small. The breadth t of the die nib wall can never be greater than the radius of the circle C_c minus the distance from the center of C_c to the inner surface of the die, when the center R of curve C_c falls within the inner face of the die, as seen in FIG. 4; but when R of curve C_c is located above the inner face of the die (see FIG. 5), the maximum thickness T_{max} of the die nib wall is computed by subtracting from the radius of C_c the distance to the inner face with a minus sign, and then this distance becomes additive instead of subtractive. Geometrically it is simpler to lay out the maximum thickness T_{max} of the die nib wall as follows: Draw a line from center of the die through the center R of the curve C_c until it reaches the described curve C_c with radius $\text{Csc Alpha}/2$. FIG. 4 shows the maximum thickness for the case where R falls within the inner face of the die. FIG. 5 shows the maximum thickness T_{max} of the die nib wall where R falls beyond the inner face of the die. The maximum breadth T_{max} of the die nib wall approaches zero as Alpha approaches 90° .

Using the same FIGS. 4 and 5 to express the maximum breadth of the die nib wall in polar coordinates, one can write the following equation:

Equation 11

$$r_1=f(\theta_1),$$

or by Equations 7 and 8,

$$r_1=\text{Sin}(\theta_1+\text{Alpha})/\text{Sin Alpha}, \text{ where } \theta_1+\text{Alpha}=90^\circ.$$

10 Then the maximum breadth $T_{max}=f(\theta_1)-1=r_1-1$; or $T_{max}=(1/\text{Sin Alpha})-1=\text{Csc Alpha}-1$. The 1 here is the unit inner die radius. This last equation is simply another way of writing Equation 10; it helps to demonstrate that θ_1 represents the polar angle 15 of the line going through the center of curve C_c .

The maximum breadth T_{max} from Equation 10 can readily be calculated; a few such calculations are given here for general consideration only;

At Alpha=60°, $T_{max}=8\%$ of the diameter of the die opening;

At Alpha=45°, $T_{max}=20\%$ of the diameter of the die opening;

At Alpha=30°, $T_{max}=50\%$ of the diameter of the die opening;

At Alpha=15°, $T_{max}=143\%$ of the diameter of the die opening.

Using Equation 9, which shows in particular that the center of C_c is on the vertical line $x=\frac{1}{2}$ (as seen in FIGS. 4 and 5), it is clear that if the center is at the point Q (which lies on a line through the origin forming an angle of 60° with the horizontal), the corresponding Alpha is 30°; for larger Alpha the center will be below Q, and for smaller Alpha the center will be above Q.

35 To construct the design of a segment: Determine the curve C_c from the polar coordinate Equation 7, keeping in mind all the other instructions given above; determine the number of segments m in accordance with the considerations given below (see Section V). Then after having drawn the first curve C_c , starting from point (1,0), rotate clockwise the design by 360/m degrees, as seen in FIG. 3, and repeat the same curve C_c again from the unrotated point (1,0).

40 II. A class of segmental die nibs favoring greater cohesive pressures between segments toward their inner face vertices, under conditions of equally radiated work stresses; and tending to equalize the cohesive pressures, when the work stresses are radiated out with less force toward the inner face vertices than toward points farther along the interfaces of the segments (see FIGS. 6, 7, 8, 9, 10, 11, 33, and 35).

45 In operations such as cold forming, extrusion, and the like, the radial pressures exerted against the inner faces of a polygonal die are not equal in all directions, but are greater toward the middle of the sides and less toward the vertices. This is illustrated when circular stock material is being drawn through, being reshaped in the working processes from a starting stock material to some geometric angular shape, as, for example, a slug being reshaped into the form of a spark plug stock; here the radial force will be greater in the direction of the midpoints of the polygons than in the direction of the vertices. This can be seen in FIG. 2A, showing a hexagonal section; it is seen that the peripheral end of the segmental curve C is more nearly opposite the facet of the hexagon than is the inner part of the curve C; hence the family of curves representing circles will not be a family of equal-pressure curves but will have the prop-

erty that the cohesive pressure increases (depending upon the angle Alpha, it might be an increase in some cases just over a certain initial range) as the distance from the center increases. Similarly, in dies with curvilinear openings (circular, elliptical, etc.), when materials of a geometrical shape different from the die opening are being drawn, extruded, sheared, etc., the work stresses are again not initially radiated out equally in all directions.

However, by a modification of the circular segmental die nib curves which form the curves C_c of Class I, a new family, Class II, of curves is produced, each of whose members C_s (see FIG. 6) has the property that the cohesive pressures between segments decrease as one moves outward from the inner face of the die, when the work stresses are radiated out equally from the central axis of the die opening. Thus the tendency of the die nib segments to separate at their inner vertices under the conditions just discussed above will be overcome by these new curves C_s , which will favor an equalization of cohesive pressures between segments, when the work stresses are radiated out with less force toward the inner face vertices than toward points farther along the interfaces of the segments. Otherwise, the separation would permit small particles to occlude in the formed crevices, causing streaking, and with each succeeding impact this occlusion and separation would tend to worsen.

Each curve of Class II differs from its correspondent in Class I, which has the same initial angle Alpha, in that it curls around more slowly. Given such an initial angle Alpha, there are many curves of Class II which begin at this angle. However, every curve of Class II satisfies the condition (from Equation 5) that:

$$\sqrt{[f'(\theta)]^2+[f(\theta)]^2}$$

is an *increasing* (or nondecreasing) function of θ , where $r=f(\theta)$ is the equation of the curve. In other words, its first derivative has to be positive:

Inequality 12a:

$$2f'(\theta) [f''(\theta)+f(\theta)] > 0.$$

Since in most cases one is concerned with here $f'(\theta) > 0$,

Inequality 12b:

$$f'(\theta)+f(\theta) > 0.$$

There is no limit to the number of formulas that can be given for curves which satisfy this condition. A few selected types are here given for illustration:

1. A set of curves which have the property that the cohesive pressure drops off as $1/r$, where r is the distance to the center of the die opening, is the class of logarithmic spirals with polar equation:

Equation 13a

$$r=e^{\theta \cot \text{Alpha}},$$

where Alpha has the same significance as before. This family of logarithmic spirals given by Equation 13a, also has the property that the angle Alpha between the radial vector and the tangent to the spiral is constant (see FIG. 12). The choice of this angle Alpha not only determines how great the cohesive pressures are between segments of the die nib (the greater the angle Alpha, the greater the initial cohesive pressure toward the inner face), but also where the segmental curves end on the periphery of the die nib. If the wall breadth of the

die nib is represented by some multiple T of the radius of the die opening, and the polar angle the segmental curve sweeps through by S , then one has:

Equation 14a

$$T=d^{SCot \text{Alpha}}-1.$$

If $S \neq 0$ and $\text{Alpha} \neq 90^\circ$, then $T > 0$. In general, if one wants the die nib wall breadth to be at least a certain minimum multiple T_1 of the radius of the die opening, one can determine the relationship S and Alpha must bear to each other by:

Equation 14b

$$\tan \text{Alpha} \leq S/\log_e(T_1+1).$$

15 Thus the greater Alpha is, the larger S must be for a given T_1 , and the more the die nib would tend toward a quasi-laminar form. In certain die operations where the work stresses are extremely great, this would be a valuable asset, although one would always want S less than π in order to make the manufacture of the segments feasible. Thus if $T_1=1$, Alpha would have to be $\leq 77^\circ 34'$. In particular, if Alpha were 50° and S were $\pi/2$, then T by Equation 14a would be 2.74; if Alpha were smaller or S larger (but not greater than π), then T would have to be correspondingly larger; and if Alpha were larger (but less than $77^\circ 34'$) or S smaller (but not less than 0.83), then T would be correspondingly smaller (but not less than 1). One, of course, can set the limits according to Equations 14a and b to fit 20 whatever the particular die operation calls for. One not only has a Class II curve favoring greater intersegmental cohesive pressures toward the inner face of the die, but one has control of the initial angle Alpha, the point the segmental curves end on the periphery of the die nib, and within desired limits the breadth of the die nib wall.

2. When $\text{Alpha}=45^\circ$, Equation 13a becomes
Equation 13b

$$r=e^\theta, \text{ since } \cot 45^\circ=1.$$

3. Straight line segmental curves also obey the criteria for curves of Class II (see FIGS. 7, 8, and 9). They can be expressed in polar coordinates by
Equation 15

$$r=f(\theta)=\tan \text{Alpha}/(\cos \theta \tan \text{Alpha}-\sin \theta).$$

However, it should be observed that when the die opening configuration is a polygon of m sides, the initial angle Alpha (which the straight line segmental curve makes with the horizontal) should be chosen according to the following criteria:

i. If $m \leq 8$ (as in FIGS. 8, 10, and 11), in order to provide superior cohesion between die segments and to obviate displacement through torque of the segments toward the periphery of the die nib, the range of Alpha should be limited by the following inequality:

Inequality 16a

$$90^\circ-(180^\circ/m) < \text{Alpha} < 90^\circ+(180^\circ/m).$$

60 In particular, by an appropriate choice of Alpha, depending on the breadth of the die nib, one can have the first straight line segmental curve end at the polar angle corresponding to the start of the next straight line segmental curve (see FIG. 8). This will insure both that the cohesion between the die nib segments will be adequate and that the inner face corners of the die nib segments will not be frangible.

ii. If $m > 8$ (as in FIG. 9), in order to prevent the inner face corners of the die segments from being too fragile, the range of Alpha should be limited by the following inequality:

Inequality 16b

$$0 < \text{Alpha} < 90^\circ - (180^\circ/m)$$

Here again, depending on the number of sides of the polygonal die opening and the breadth of the die nib, one can choose an angle Alpha such that the first straight line segmental curve ends at the polar angle corresponding to the start of the next straight line segmental curve (see FIG. 9).

The ratio of cohesive forces between segments at the inner face of the die to that at the periphery of the die nib is greater with straight line segmental curves than with logarithmic spirals having the same initial Alpha (of Equation 13a), since the spirals curl around faster than the straight lines. However, the polar angle S which the curve sweeps through before ending at the periphery of the die nib will be greater for the logarithmic spirals than for the straight lines with the same initial Alpha. This would allow the die better to withstand greater work stresses than with the straight line segmental curves; at the same time, the inner corners of the segments would not have to be as pointed. The advantage, of course, of the straight line segments is their simplicity of layout, and in cases where they give sufficient intersegmental cohesive pressures they will be found useful.

4. To maximize the ratio of cohesive pressures between segments at the inner face to the periphery of the die nib, curves curling around clockwise instead of counterclockwise may be used (as illustrated in FIGS. 14, 14a, and 14b). Those whose tangent at $r=1, \theta=0$ (or $x=1, y=0$) is perpendicular to the radius vector to that point provide the greatest cohesive pressure between segments at the inner face of the die opening, since in this case Beta of Equation 2 would be 90° and thus Sin Beta at its maximum possible value, 1. A number of families of such curves are given by the following generic equation for conic sections:

Equation 17a

$$y^2 + a(x - (1+w))^2 = d(x - (1+w)) + e,$$

where $w = (-d \pm \sqrt{d^2 + 4ae})/2a$ for $a \neq 0$, and $w = e/d$ for $a = 0$.

i. When $d = 0, a = 1$, and $w^2 = e$, one has a family of circles whose center is at $x = 1+w$, $y = 0$, and whose radius is w ($= \sqrt{e}$).

ii. When $d = 0$ and $w^2 = e/a$, one has a family of ellipses whose center is at $x = 1+w$, $y = 0$, and the lengths of whose semi-axes are w and $\sqrt{e}$.

iii. When $a = 0, e < 0$, and $w = -e/d$, one has a family of parabolas whose focus is at $x = 1+d/4$, $y = 0$, and whose directrix is $x = 1-d/4$.

iv. When $d = 0, a < 0$, and $w = -\sqrt{e}/a$, one has a family of hyperbolas whose right-hand focus is at $x = 1+w(1 - \sqrt{1-a})$, $y = 0$, whose center is at $x = 1+w$, $y = 0$, and whose apex is at $x = 1$, $y = 0$.

To obtain conic sections whose tangent at $r = 1, \theta = 0$

5

(or $x = 1, y = 0$) forms some angle Delta $> 90^\circ$ with the radius vector to that point, one can modify slightly Equation 17a to

Equation 17b

$$(y-z)^2 + a(x - (1+w))^2 = b(y-z)(x - (1+w)) + c(y-z) + d(x - (1+w)) + e,$$

where $w = [bz - d \pm \sqrt{(bz - d)^2 - 4a(z^2 + cz - e)}]/2a$ for $a \neq 0$, and $w = (z^2 + cz - e)/(bz - d)$ for $a = 0$.

One can also reflect the counterclockwise curves of Classes I and II above and of Class III below along a line D—D', as, for example, in FIG. 14B, passing through the point $r = 1, \theta = 0$ (or $x = 1, y = 0$) and making with the horizontal a positive angle Gamma ($\leq 90^\circ$ for polygonal die openings of 8 or fewer sides, and $\leq 45^\circ$ for other polygonal or curvilinear die openings), to obtain mirror-image clockwise curves, whose tangent to that point makes an angle of $180 + \text{Alpha} - 2\Gamma$ with the horizontal (as shown in FIG. 14b). This is most easily done by traditional graphical procedures.

Various mathematical transformations are also possible, but they are more complex than the graphical methods. For illustration, one of a variety of mathematical transformations yielding the desired results is given below:

Equation 17c

$$x = r \cos(2\Gamma - \theta) + 2 \sin^2 \Gamma$$

$$y = r \sin(2\Gamma - \theta) - \sin 2\Gamma$$

35 Equation 17d

$$\theta' = \tan^{-1}(y/x)$$

$$r' = \sqrt{x^2 + y^2},$$

40

where r' and θ' are coordinates of the reflected curve.

From Equations 17c and 17d it becomes obvious that when the radial vector to the point (r', θ', θ') is coincident with the tangent of the curve at that point, this is where the radial force will result in the least cohesive pressure and hence the ratio of the cohesive pressure at the inner face of the die opening to that of the abovementioned point is the maximum ratio. Practically, it means that when work stresses are very great and would otherwise tend to push the die segments apart sufficiently to cause various complications (such as accumulation of small particles between segments, causing streaks on the work surface of the article and mechanical damage to the corners of the segments), then by using segments made by reflecting counterclockwise curves of Classes I, II, and III, the cohesive pressures at the inner faces between segments are greater than what one would obtain by using the counterclockwise curves described in this application.

To illustrate the mathematically derived reflection of curves about a line D—D' (as illustrated in FIG. 14B), conversion tables (obtained from Equations 17c and 17d) are given below for a set of Class II curves given by Equation 13a ($r = e^{-\text{CotAlpha}}$), where Alpha and Gamma assume sample pairs of values (see FIG. 14B).

For Gamma 15°
Alpha 10°

r	θ°	x	y	r'	θ'°

* The radial vector passing through the point given by this r' , θ' is coincident with the tangent of the curve at this point, and this is where the radial force will result in the least cohesive pressure and hence the ratio of the cohesive pressure at the inner face to that at this given point is the maximum.

The above described reflected curves can all be continued up to the angle θ'_L , where the radius vector becomes coincident with the tangent to the curve at that point (see FIG. 14b). This would determine the maximum breadth of the die nib wall for the particular curve. For instance, in the case of circles whose center is at $r=w+1$, $\theta=0$, and whose radius is w (see Equation 17a-i), one would have $\sin\theta'_L=(w/1+w)$ and $t_{max}=271+2w-1$. It should be noted that curves continued up to this point have the property of providing no cohesive pressure between segments at the periphery of the die nib. This should be kept in mind when considering their use, as, for example, in the drawing of very small diameter wire.

III. A class of segmental die nibs where the cohesive pressures between segments increase over a determined range of the segmental curves C_f starting from the inner face of the die, under conditions of equally radiated work stresses; and where the cohesive pressures tend to be equalized, when the work stresses are radiated out with greater force toward the inner face vertices than toward points farther along the interfaces of the segments (see FIGS. 6, 15, 16, 17, 18, 19, 34, and 35).

In operations where intermittent impacts and inconstant generated work pressures demand a certain degree of "give" or elastic response in the inner aspect of the die to prevent premature failures, the die nib segments have to be so designed as to absorb the shock by appropriate yielding at the inner face created by increasing cohesion of the segments over a certain range of the segmental curve, starting from the inner face of the die. For example, this would be the case with a hot rolled, pickled, irregular surface, with under certain

35 conditions might cause chattering and early failure of the die. Another example would be in the case of fabricating parts from powder metals. Further examples, among others, are given on pages 44-46 (Example 3) and pages 46-47, 48 (curve C of Example 4).

40 Another modification of the circles which form the curves C_c of Class I produces a new family, Class III, each of whose members has the property that the cohesive pressures increase over a certain range of the interface as one moves outward from the inner face of the die, when the work stresses are radiated out equally from the central axis of the die opening. This characteristic of cohesive pressure differential can be likened to a stress shock absorbing or cushioning effect. Each curve of Class III differs from its correspondent in Class

45 I, which has the same initial angle Alpha, in that it curls around more rapidly for the early part of its range. Given such an initial angle Alpha, there are many curves of Class III which begin at this angle, even in the subfamily described by Equation 19 below.

50 Every curve of Class III satisfies the condition (from Equation 5) that:

$\sqrt{[f'(\theta)]^2+[f(\theta)]^2}$ is a decreasing function of θ over some initial range $0 \leq \theta < \theta_{max}$, and where $r=f(\theta)$ is the equation of the curves. This condition gives rise to the

60 differential inequality:

Inequality 18

$$f(\theta) + f'(\theta) < 0,$$

65 which is satisfied by all curves of the subfamily described by Equation 19, as will be seen.

There is no limit to the number of formulas that can be given for curves which satisfy this condition. Even

Equation 19 below describes a doubly infinite family, and K and n take on various positive values (however, too small values of K and n less than 1.5 in this formula will not produce curves of Class III; see Inequality 23 below). A few general considerations and selected types are given below as illustrations:

A class of spirals satisfying the above condition has as its polar equation:

Equation 19

$$r=K[(1/K)^n+\theta]^{1/n}=f(\theta),$$

where K and n are independent positive constants. Illustrations are given below on how to select practical values of K and n (see Equations 24 and 25 below, and pages 28, 29, FIGS. 36 and 36a).

For each curve of this set of spirals (i.e., for a given K and n), there is a θ_{max} which determines the point M on the curve (as shown in FIGS. 15, 16, 17, 19, and 19), at which there is the maximum cohesive pressure between segments of a die nib designed in accordance with this curve. Up to this point M , the cohesive pressures between the segments of the die nib have been increasing starting from the inner face; after this point M , they slowly fall off. However, if one wants to modify the rate at which the cohesive pressures fall off (either increasing the rate or making the rate equal to zero, i.e., maintaining equal cohesive pressures between segments after the point M), one can substitute curves from Class II or I, starting from the point M onward, for the remaining portion of the original curve (see FIG. 2c).

To determine θ_{max} , one has to consider Equation 5, given above in Part I, for the cohesive pressure P between segments:

$$P=H/\sqrt{[f'(\theta)]^2+[f(\theta)]^2}.$$

In order for P to be an increasing function of θ , starting from the inner face of the die, $[f'(\theta)]^2+[f(\theta)]^2$ has to be a decreasing function of θ . In other words, its first derivative, $2f'(\theta)[f'(\theta)+f(\theta)]$, has to be negative. For the curve given by Equation 19, $f'(\theta)=(K/n)[(1/K)^n+\theta]^{1-n/n}$, $2f'(\theta)$ is always positive in the case under consideration. Therefore $f'(\theta)+f(\theta)$, or $[K(1-n)/n^2][(1/K)^n+\theta]^{1-2n/n}+K[(1/K)^n+\theta]^{1/n}$ has to be negative for $0 \leq \theta < \theta_{max}$, and $=0$ for θ_{max} .

In other words:

Equation 20

$$\theta_{max} = \sqrt{n-1}/n - (1/K)^n \text{ (in radians).}$$

Solving in Equation 19 for the r corresponding to θ_{max} , one has:

Equation 21

$$r_{\theta_{max}} = K(\sqrt{n-1}/n)^{1/n}$$

By Equation 3 above:

$f(\theta) \operatorname{Cot} \text{Beta} = f'(\theta)$, where Beta is the angle between the tangent to the curve $r=f(\theta)$ at any point and the radius vector to that point.

In particular, when Beta=Alpha (where Alpha has the same significance as in the rest of the text), for the curve given by Equation 19, $\theta=0$, and

$$f(0) \operatorname{Cot} \text{Alpha} = K/n[(1/K)^n]^{1/n}.$$

Since $f(0)=K[(1/K)^n+\theta]^{1/n}$ (for Equation 19), one obtains:

Equation 22

$$\operatorname{Cot} \text{Alpha} = (K/n)(1/K)^{1-n} = K/n^n.$$

Thus one sees from Equations 20 and 22 that θ_{max} and Alpha can be determined by given K and n ; conversely, K and n can be determined by given θ_{max} and Alpha, as will be shown by Equations 24 and 25 below.

To establish practical values of K and n , it is useful first to eliminate by inspection extreme values of K and n :

Firstly,

$$\lim_{K \rightarrow \infty} \operatorname{Cot} \text{Alpha} = \infty,$$

so that for large K , Alpha is near 0° , an undesirable value because this implies small cohesive pressure at the inner face.

Secondly,

$$\lim_{n \rightarrow \infty} \operatorname{Cot} \text{Alpha} = \infty,$$

giving the same observation for large n . Therefore practical values of K and n will not be very large.

On the other hand, values of K and n near or below 1 produce curves which do not satisfy the conditions which define curves of Class III. Even $K=1.5$, $n=1.5$ fail to do so.

The relationship between K and n , which determines curves of Class III in Equation 19, can be derived from Equation 20, since θ_{max} has to be positive. Thus

$$n-1/n - (1/K)^n > 0, \text{ or}$$

Inequality 23

$$K > (n^2/n-1)^{1/2n}.$$

It is thus seen that when n is only slightly greater than 1, K has to be large, and vice versa.

If one solves Equations 20 and 22 for n in terms of Alpha and θ_{max} , one obtains:

$$\text{Equation 24} = [1-2\theta_{max}(\operatorname{Tan} \text{Alpha}) - \sqrt{1-4\theta_{max}(\operatorname{Tan} \text{Alpha})-4(\theta_{max})^2}]/2(\theta_{max})^2,$$

where Alpha is in degrees and θ_{max} in radians.

Once one has obtained n by Equation 24, one can solve for K in terms of Alpha and θ_{max} by using Equation 22, $\operatorname{Cot} \text{Alpha} = K^n/n$, or

Equation 25

$$K = (n \operatorname{Cot} \text{Alpha})^{1/n}, \text{ where } n \text{ is given by Equation 24.}$$

In order for n to be a real number in Equation 24, $1-4\theta_{max}(\operatorname{Tan} \text{Alpha})-4(\theta_{max})^2$ cannot be negative. If one sets this quantity equal to zero and solves for θ_{max} , one can then determine the largest value θ_{max} can ever have no matter what n and k one tries to choose. One thus obtains

Equation 26

$$\theta'_{max} = (1-\operatorname{Sin} \text{Alpha}')/(2 \operatorname{Cos} \text{Alpha}'),$$

which for $\text{Alpha}'=0^\circ$ assumes its largest $\theta'_{max} = \frac{1}{2}$ radian, or $28^\circ 36'$. Similarly, when Alpha' approaches 90° , θ'_{max} has to approach 0° .

Before Alpha and θ_{max} are chosen to determine a particular segmental curve of Equation 19 in Class III for a specific die operation, the following general criteria should be considered:

1. Finished properties of the work material:
  - a. If surface finish is extremely important, one wants θ_{max} as close to the innerface as possible.

b. If resistance to instantaneous shock of the work material is the dominant factor, as in mitigating die explosion, one wants θ_{max} farther out from the interface of the die. This displacement outward of the point of maximum cohesive pressure permits a certain give between the segments from the inner face to the point M (corresponding to θ_{max} , $r_{\theta_{max}}$)

18 to act as a damping shock absorber. All other conditions prescribed in the text are interdependent and must be observed. (See Sections IV and V, Equations 5, 19, 20, 21, 22, 24, and 25, and the text treating the meaning of these conditions.)

2. Early die failures due to chipping can be avoided by having the initial angle Alpha as small as is practicable. All other conditions given in the text (as enumerated in (1)(b) above) must be complied with.

3. If chipping is not the dominant factor of the die failure, as in fabricating parts from powders, ductile metals, small extrusion reductions and the like, then the angle Alpha can assume larger values compatible with all the other conditions given in the text and immediately above under (1)(b).

4. From a practical consideration, the angle Alpha can be considered to be between 10° and 70° for polygonal die openings, and between 10° and 50° for round-shaped openings.

5. As has already been pointed out under Equation 26, θ_{max} has to be between 0° and $28^\circ 36'$.

6. The value of $r_{\theta_{max}}$ (that is, $f(\theta_{max})$), corresponding to θ_{max} , minus the unit radius of the die opening, gives the breadth of the die nib wall at the point of maximum cohesive pressure between the segments. It should be noted, however, that the curve solving Equation 19 can be extended beyond θ_{max} without disturbing the fact that the curve is of Class III, having increasing interface cohesive pressures over the range $0 \leq \theta \leq \theta_{max}$. For certain types of dies, industry usually likes to have the breadth of the die nib wall at least equal to the radius of the die opening. Therefore one can solve Equation 19 with given n and K for $r=2$, in order to determine the angle θ to which one has to continue the segmental curve in order to obtain the appropriate die nib wall breadth. However, in this case, Alpha and θ_{max} cannot be chosen independently of each other. Alpha firstly determines the upper limit of n_{Alpha} by

Equation 27

$$\text{Tan Alpha} = \frac{n_{Alpha} S}{2n_{Alpha} - 1}$$

where S represents the polar angle in radians the segmental curve sweeps through before ending at the periphery of the die nib. For instance, if the segmental curve starts out at $r=1$, $\theta=0^\circ$ and ends at $r=2$, $\theta=90^\circ$, then $S=\pi/2$ or 1.5708, and one has

$$\text{Tan Alpha} = \frac{1.5708 n_{Alpha}}{2n_{Alpha} - 1}$$

If one graphs Equation 27 for $S=\pi/2$ (as in Graph 20), or for $S=\pi/3$ (as in Graph 22), to take particular examples, one sees what n_{Alpha} corresponds to each given Alpha for these cases. One then solves for K in Equation 25, and finally by Equation 20 one can determine the upper limit of θ_{max} corresponding to each given Alpha. This relationship, again for a die nib whose wall breadth is equal to the radius of the inner die opening when $S=\pi/2$, is given by Graph 21, and when $S=\pi/3$, by Graph 23. It means that for any given Alpha, one can

choose θ_{max} only between 0° and the θ_{max} corresponding to that Alpha on the graph, although, unless one chooses the exact corresponding θ_{max} , the die wall breadth will be proportionately thicker than the radius of the inner die opening. It should also be noted that the upper limit for Alpha itself is determined by the n -solving

Equation 28

$$2\frac{n}{\alpha} - 1 = (n_{\alpha} S) / n_{\alpha} - 1$$

10 It is convenient to use Newton's approximation method to solve for this n . One first determines the function

$$g(n_{\alpha}) = n_{\alpha} S / n_{\alpha} - 1 - (2\frac{n}{\alpha} - 1) = 0$$

One then tries some arbitrary n_{α}^* . If $g(n_{\alpha}^*) \neq 0$, then one corrects the n^* by:

$$n_{\alpha}^{**} = n_{\alpha}^* - [g(n_{\alpha}^*) / g'(n_{\alpha}^*)]$$

20 If the corrected value still does not give $g(n_{\alpha}^{**})=0$, one corrects it once or twice more by the same method until $g(n_{\alpha}^{****})=0$. The following are some sample calculations: When $S=\pi/2$, $n_{\alpha}=2.06$, and Alpha= $45^\circ 40'$ (by Equation 27); the corresponding $\theta_{max}=0^\circ$. When $S=\pi/3=1.0472$ (or 60°), $n_{\alpha}=1.65$, and Alpha= $38^\circ 55'$; again the corresponding θ_{max} for this maximum Alpha, as will always be the case, is 0° .

In general, if one wants the breadth of the die wall to be some other multiple T of the radius of the die opening, one has to modify slightly Equation 27 to:

Equation 29

$$\text{Tan Alpha} = n_{\alpha} S / [(T+1)^n_{\alpha} - 1]$$

35 where S has the same meaning as before, that is, it is the angle θ in radians corresponding to $r=T+1$ (refer to Equation 19). Equation 28 giving the n_{α} corresponding to the upper limit of Alpha also has to be slightly modified to

40 Equation 30

$$(T+1)^n_{\alpha} - 1 = (n_{\alpha} S) / n_{\alpha} - 1$$

To solve for the n_{α} in Equation 29 and the n_{α} in Equation 30, it is convenient to use here again Newton's approximation method as explained under Equation 28, but where $(T+1)$ replaces the 2. In Graph 24, Equation 29 is graphed for $T=0.5$, $S=\pi/4$ (or 45°); in Graph 26, for $T=0.5$, $S=\pi/3$ (or 60°). In Graph 25, the upper limit for values of θ_{max} corresponding to given 50 Alpha is graphed when $T=0.5$, $S=\pi/3$; in Graph 27, when $T=0.5$, $S=\pi/3$.

55 It is evident from the above that once three out of the four variable constants T , S , Alpha and θ_{max} have been chosen, the fourth one is already determined by them.

55 If one is interested in a particular value of Alpha corresponding to a particular value of θ_{max} , or vice versa, instead of their entire range of values (as illustrated in Graphs 21, 23, 25, and 27), one does not have to draw all the graphs mentioned above:

60 a. In the case where T , S , and an Alpha below its upper limit (see Equations 30 and 29) are given, one solves by Newton's approximation (see under Equation 28) method for the corresponding n in Equation 29, then determines K by Equation 25, and finally θ_{max} from Equation 20.

65 b. In the case where T , S , and a θ_{max} (in radians) below its upper limit are given, one solves by New-

ton's approximation method (see under Equation 28) for $n_{\theta_{\max}}$ in the following Equation 31

$$\sqrt{n_{\theta_{\max}}} - 1 - n_{\theta_{\max}}(\theta_{\max}) = \frac{n_{\theta_{\max}} S'}{(T+1)n_{\theta_{\max}} - 1}$$

The advantage of being able to prescribe T and S for a curve is evident when one considers the relationship of the segments to each other. One can either have the first segmental curve end before, at, or after the polar angle corresponding to the start of the next segmental curve. This determines to what extent the segments will overlap each other, for the farther along the first curve ends in relationship to the polar angle the next curve begins at, the more the die tends to a quasi-laminar form, as illustrated in FIGS. 28-30. In certain operations, such as large radius reductions, this is a valuable asset; while for small radius reductions one would want segmental curves that ended short of the polar angle corresponding to the start of the next curve. (7) When a die is intended to be reused by opening its inner diameter to larger sizes, the original $r_{\theta_{\max}}$ (corresponding to $\theta_{\max}$; see Equations 20 and 21) has to be chosen large enough to allow the point of maximum cohesive pressure between segments still to correspond to the conditions prescribed for the original die design.

Once one has selected the appropriate Alpha and $\theta_{\max}$ according to the above criteria, one solves for n in Equation 24 and then for K in Equation 25. One then substitutes these values of n and K into the generic Equation 19. One thus obtains a specific equation for the desired segmental curve, which can then be graphed in polar coordinates, as in FIGS. 15, 16, 17, 18, 19, 34, and Curve C of FIG. 35, and from which one can make a templet.

Many other curves besides those given by Equation 19 will satisfy the criteria of Class III curves (see Inequality 18 and accompanying text); but all of them will be only slight variations, within the θ range which defines them as Class III curves, on those that can be obtained by appropriate choice of n and K in Equation 19.

For convenience, a chart is set up below (see FIGS. 36 and 36a) of some representatively useful pairs of values for n and K corresponding to particular given $\theta_{\max}$ and initial angle Alpha. Outlined in yellow (4) is the range of values for $T=1, S=\pi/3$; in red (3) the range of values for $T=1, S=\pi/2$; in brown (2) the range of values for $T=0.5, S=\pi/4$; in purple (1) the range of values for $T=0.5, S=\pi/3$.

IV. Some important general considerations about the angle Alpha in segmental die design:

i. LIMITS for Alpha:

When the segmental curves are of Class I (circles C_c) or Class III (curves C_f curling around faster than C_c (see FIG. 6)), the choice of Alpha is limited between an angle greater than 0° and less than 90° .

However, in curves of Class II (curves C_s curling around more slowly than C_c (see FIG. 6)), or in straight lines, Alpha can be even greater than 90° . Its theoretical limit in the case of straight lines is an angle less than $90^\circ + (180^\circ/m)$ (see II, 3 above, pp. 19-20). For the more slowly curling curves C_s , Alpha has to be varingly smaller than this, depending on the nature of the particular curve chosen (as, for example, curves represented by the Equations 13a, 13b, and 14a).

ii. Some simple guides for the CHOICE of Alpha:

The larger Alpha is chosen, the greater is the cohesive pressure between the segments toward the center.

In the case of curves of Class II (curves C_s curling around more slowly than C_c (see FIG. 6)), as in Equations 13a, 13b, 14a, or in straight lines, the breadth t of the die nib wall is not as limited as in the case of curves of Class I (circular curves C_c) with the same initial angle Alpha. In fact, when a straight line is used, the breadth t of the die wall can be made as large as one desires; there is no theoretical limit.

However, in the case of curves of Class I (circular curves C_c), the larger Alpha is, the small $t_{\max}$ is, in accordance with the formula given by Equation 10 (for specific examples, see pages 14-15).

For curves of Class III (curves C_f curling around faster than C_c (see FIG. 6)), $n_{\theta_{\max}}$ is even smaller than in the case of corresponding circular curves C_c with the same initial angle Alpha (see pp. 28-29 and Equation 21, p. 27). However, the breadth t of the die wall can be made to suit whatever one's needs are (see pages 28 et seq.).

iii. Relationship of COHESIVE pressures to various types of curves with the same initial Alpha:

For any given Alpha, reverse curves as given by Equations 17a through 17d give the greatest cohesive pressures between segments toward the innerface (see FIGS. 14, 14a). Other curves of Class II, including the straight line with

$$90^\circ - (180^\circ/m) < \text{Alpha} < 90^\circ + (180^\circ/m),$$

(see FIG. 6), have a smaller ratio of cohesive pressures at the innerface to the periphery of the die nib than the reverse spirals with the same Alpha; the corresponding circular curve C_c of Class I has an even smaller ratio; and curves of Class III (C_f in FIG. 6) have the smallest ratio of all in the range $0^\circ < \theta < \theta_{\max}$ (as defined above on pages 26-27). In fact, they would initially favor greater cohesion away from the innerface than toward the innerface. In the case when all work stresses are radiated equally in all directions against the inner face of the die, the cohesive pressure for a circular curve C_c will be the same along the entire arc between the segments: in other words, the ratio of cohesive pressures at the center to the periphery of the die is in this case 1.

iv. As mentioned in the case of circular curves C_c , the greater the initial Alpha, the more pointed become the inner corners of the segments and consequently the more apt to chip than when Alpha is small. This property applies to all types of curves, including the straight lines, which have been discussed above. As mentioned before, the greater the Alpha the greater the cohesive pressures toward the inner face of the die. This property, even when taken in conjunction with the possibility just mentioned of chipping of the inner corners of the segments, can serve to advantage for fashioning certain types of metals, and can permit the number of segments in the die nib to be greater than the number of sides of the polygon; when the inner opening is a circle or another type of curve, the number of segments can, of course, also be as great as one wants. The result is a good serviceable inner face of a die with less tendency to streaking or explosion than in the case of dies whose segments are designed by conventional means.

v. Some important general considerations about the choice of the number of segments m in segmental die design:

Several practical considerations, among other requirements, govern the choice of the number of segments m , whether the segmental curves are of Class I (C_c or circular, as discussed in Part I above), of Class II (C_s or curling around more slowly than circles, as discussed in part II above), or of Class III (C_f or curling around faster than circles, as discussed in part III above):

1. If one wants the curves C to start only from the vertices of a polygonal die center, the number of segments m is limited to the number of sides of the polygonal opening. In selected cases, the number of segments could be reduced further: for example, in a hexagonal die, three segments; in an octagonal die, four segments, and so forth. In a polygon having four or three sides, it is practical to have the number of segments correspond to the number of sides.

In some cases of polygonal dies, as in the specific example of a hexagon illustrated in FIG. 13, the vertices are not pointed out but instead might assume the shape of some curve or straight line (the latter case being shown in FIG. 13). Each segment can incorporate the additional change in the geometric polygon by having the point of its inner face start at the beginning of the vertex curve; the next segment would start at the corresponding beginning of the next vertex (again as illustrated in FIG. 13). All other considerations, as to the type of curve C , the angle Alpha, the breadth of the die nib, and other points discussed above, can then disregard the change in the vertices on the inner surface of the die.

Theoretically, the number of segments can be greater than the number of sides of the polygon. However, the length of the curves C starting from the intermediate points along the sides of the polygon will be greater than for those starting at the vertices. The maximum breadth t_{max} of the die wall will therefore be determined by the longest of these curves, which in the case of curves of Class I (C_c or circular) is limited by the considerations given above (see pages 13-14). Of course, when the die opening is circular, elliptical, or of some other curvilinear shape, the number of segments can be as great as one practically wants.

Even when the die opening is of some irregular shape, as in FIG. 31, segments can be made in accordance with the criteria of this application. In such cases, however, the segments will not all have the same overall shape; although the segmental curves may all be derived from the same equation, some may be longer or shorter than others, depending on the geometry of the die. This also is illustrated in FIG. 31, where for convenience the straight part of the die is made in a single section. In other cases, however, the segmental curves may even belong to different classes from one another, if the unequal distribution of work forces against the inner face at the die so calls for it. This is illustrated in Example 4 of Section VI and FIG. 35. The important point to keep in mind is the class of curve to choose, as indicated in this application, appropriate to the type of work involved. Then all other considerations for the number of segments, the initial angle Alpha, the breadth of the die nib wall, and so forth, will be the same as discussed in the appropriate places of this application.

2. The rule of thumb employed is the following: When the metal-working is too severe on the die and causes early die failure, the stresses generated by such hard metal-forming might better be met with a greater number of segments. In cold-forming, or impact extrusion, where dimensions are highly critical and die life only secondary to the finished tolerances, the number of segments, Alpha, and the shape of the curve are more critically interrelated.

The segments as produced in accordance with the present invention are assembled and processed within one or more shrink rings, finished to the exact dimensions and geometry in the usual manner, and employed in a die block and/or retainer. The die block, or die holder or retainer, constitutes an important step in the utilization of the potentials of even a good die, as claimed by this application. In practice, the trade would prefer to have the breadth wall of a die block equal to, or, if space permits, greater than, the total diameter of the die nib and the shrink ring or rings upon the nib. This is especially true where tolerances are critical, within about $0.0032''$ - $0.0012''$, as, for example, in chipless machining, or impact extrusion, where the work pressure on the walls is intermittent and instantaneous, and, as soon as the metal begins to flow, falls down very rapidly. General considerations in a good die and die case are to keep all size tolerances of the work piece critical, to have the work piece produced as clean as possible, and to have good die life. By using all the considerations recited in this application, the objectives just mentioned are more superiorly attained than with a similar die not conforming to the criteria given in this application.

In carrying out the present invention, any materials may be used for fabricating dies that are at present employed in connection with die-forming operations, as, for example, extrusion (in any of its various forms, such as forward, backward, impact reduction, etc.); drawing, both hot and cold; upsetting, trimming, punching, shearing, and other operations in fashioning metals or non-metals, such as plastics of various types. Thus the dies may be made of any appropriate metals and alloys, such as tungsten carbide steels, tool steels, monel metal, metals such as iron, cobalt, nickel, copper, and other transition series metals, particularly of small particle size, such as below three microns.

The materials subjected to die shaping and forming in accordance with the present invention include metals and plastics used today in die-forming or shaping operations, such as hard and semi-hard metals, such as brass; and steel, such as stainless, rustless, chromium chrome nickel, ferrous steels or alloys, high-speed tool steels, etc.; tungsten carbide alloys in powder form; nylons; polyolefins, including polyethylenes, polypropylenes, polyurethanes, bakelite, and other phenol formaldehyde or related resins, transition metals as named above, etc.

VI. Sample cases of die operations and how to design the appropriate segmental die for them, utilizing the criteria in this patent application:

EXAMPLE 1

FIG. 32 illustrates a die for making ball joint studs (the making of the stud head is not shown). In order to determine the appropriate segmental curve, one first examines such known factors as the type of metal used, the reduction in area (which in this example is 28.5

percent), and the type of cold-heading operation. Here the work forces are radiated nearly equally in all directions against the inner face of the die, and one would want a segmental curve of equal pressure. One thus selects a curve of Class I.

One next considers the breadth of the die nib wall in terms of the initial angle Alpha, as given by Equation 10. Here the die nib wall breadth is to be at least 50 percent that the die opening. This corresponds to an angle Alpha of 30° (see illustrative calculations given on page 15 above), which will give good cohesive pressures between segments without making the inner face corner of the segments too pointed (see Section IV).

Having established Alpha, the next step in this example is to solve for the curve in accordance with Equation 9. One finds that its center will be at $x=\frac{1}{2}$, $y=\text{Cot } 30^\circ/2=0.866$; and its radius will be $1/2 \sin 30^\circ = 1$ unit (the radius of the die opening being considered as the unit). The curve is plotted as indicated in FIG. 32.

This brings one to the consideration of the number of segments to be employed. General criteria are given in Section V, and, accordingly, six segments are selected. One also knows from page 15 that when Alpha=30°, the segmental curve will sweep through a polar angle of 60° before reaching t_{max} . This means that with six segments, each segmental curve will start at the polar angle at which the preceding one ended. This allows the die to withstand better the work stresses than if the segmental curves ended short of this point.

One now rotates the coordinates of the design by $360^\circ/6 = 60^\circ$ and draws the next segmental curve from the new point $(\frac{1}{2}, 0.866)$, and continues on until all the segments are completed, as explained on page 15 and illustrated in FIG. 32.

For designing the shrink ring and casing, and in the finish of the die, accepted standard procedures are followed (see page 40).

EXAMPLE 2

FIG. 33 illustrates a hexagonal extrusion die. As discussed on pages 15-16, the work forces exerted in this case against the inner face of the die are greater toward the midpoints of the sides than toward the vertices. In order to obviate the tendency of the segments under stress to separate at the vertices, as might be the case in conventionally designed segmental dies, segmental curves of Class II should be selected for this operation. They will favor an equalization of cohesive pressures between segments under the present conditions of work stresses being radiated out with less force toward the inner face vertices than toward points farther along the interfaces of the segments (see pages 16 and 17).

Among the curves in Class II, one might choose the straight line and design the segments as shown in FIG. 8. However, because of the severity of the work stresses in this example operation, a curve from the family given by Equation 13a will serve to better advantage: for a given S and T (see Equation 14a), it will have a less sharp inner corner than its straight line correspondent; furthermore, if they both start with the same initial Alpha, it will sweep through a greater polar angle before ending on the periphery of the die than the straight line would, and this will allow the die to withstand greater work stresses (see pages 18 and 20).

For the same reasons as those in Example 1, S is chosen to be 1.0472 radians (or 60°), and the breadth

of the die wall is given as 1 unit. Substituting these values in Equation 14a, one obtains Alpha=56°30'.

One substitutes this Alpha into Equation 13a and plots the resulting curve in polar coordinates, as shown in FIG. 33. All subsequent steps for completing the die nib are the same as those explained in Example 1 above.

The alternative solutions for curves in this example are given only for the purpose of instruction and to familiarize one with utilizing all the variables to their proper advantage, which will differ from case to case. All criteria given in the text should always be used in an integrated manner.

EXAMPLE 3

FIG. 34 illustrates a die for making hexagonal shells by forward and backward extrusion. In conventionally designed dies, not only do the unequally distributed work forces of this operation cause die failure, but they also lead to such work defects in the manufactured part as "cupping" or internal rupture.

No discussion is made here of how to select the best of the few known methods of fabrication, since for the purpose of this patent application one is primarily concerned in this example with illustrating the design of the segmental die nib itself in accordance with the criteria of this application so as to withstand the given stress variations better than in conventionally constructed dies. It is assumed that it is not defects in the metals employed that cause the failures, and that there is no flexing, bending, or eventual mechanical breaking of the die due to failure of transmitting properly the pressures to the die head.

In order to prevent "cupping" in the manufactured part, to ease the stresses on the inner face of the die and allow it momentarily to correspond to the deformation geometry of the metal, it is desirable to have a slight degree of "give" between segments toward the inner face of the die. This immediately places the segmental curves in Class III, where by appropriate choice of θ_{max} this property can be set for each particular case. In this example, θ_{max} is chosen at 5° or 0.087267 radians. However, if the worked material having internal failure were of larger cross-section, θ_{max} would have to assume a correspondingly larger value.

One must now consider several factors which govern the choice of how thick the die nib wall should be: the physicals of the metal worked, the quality of the die nib material, background experience, and so forth. In this example, T is selected as 1.

Next one determines the polar angle S through which the segmental curve sweeps before ending on the periphery of the die. In cases of large stresses, as in the present example, it is usually desirable to have S equal at least $2\pi/\text{number of segments}$, so that the curves will not stop short of each other (see page 34). If the work stresses are extremely severe, then S should be even greater than this, although it should be chosen in conjunction with Alpha, so that the latter does not become too small and provide insufficient cohesion between segments at the inner face of the die. In this case, if $S=\pi/3=1.0472$ (or 60°), Alpha can be as great as 38°55' (see Equation 28 and accompanying text).

However, once three out of the four variable constants T, S, θ_{max} , and Alpha have been chosen, the remaining one is already determined by them. In this case, since $T=1$, $S=\pi/3$, and $\theta_{max}=5^\circ$, one can see from

the graph in Graph 23 or by Equations 31 and 29 that Alpha must be about 37° . This is a usable value, since it will provide sufficient cohesion between segments and at the same time will not make the inner corners too pointed or frangible, assuming the die is made out of suitable material. However, if it had turned out that the first three variable constants had determined an unsuitable value of Alpha, one or more of them would require modification to overcome this condition.

One now consults the chart in FIGS. 36 and 36a to find the n and K corresponding to $\theta_{max}=5^\circ$, Alpha= 37° . They are: $n=1.835$, $K=1.624$.

Lastly, one substitutes these values for n and K into Equation 19, and plots the resulting curve in polar coordinates, rotates the coordinates 60° , and draws it again, and continues on, as explained in Example 1, until all the segments are completed (see FIG. 34).

All subsequent steps for finishing the die nib, shrink rings, and casing follow accepted standard procedures (see page 40).

EXAMPLE 4

FIG. 35 illustrates a die for making the approximately D-shaped head of a complex bolt whose extruded shaft is not concentric with the head. Examination of the distribution of work stresses against the inner face of the die indicates that they will be greatest in the direction of the solid arrows in FIG. 35, less great in the direction of the dashed ones, and least in the direction of the dotted ones. Since segmental curves starting from any of the four vertices of the die opening would go from a point of lesser radial force to one of greater radial force over a certain initial range, they should be chosen from Class II (see pages 15-16). However, those starting from the midpoints of the longer sides (at the head of the solid arrows in FIG. 35) would go from a point of greater radial force to one of lesser radial force, and should therefore be chosen from Class III in order to provide a little "give" between segments at the inner face of the die, easing the stresses they would have to withstand.

For simplicity of design, three segments are illustrated in this example. However, if the work stresses were extremely severe, six segments could be used. The principle of design in either case would be the same.

The die openings of this example is laid out in polar coordinates in FIG. 35. For convenience, in plotting, instead of its center lying on the origin, the midpoint of its straight edge passes through there. For Curves A and B, the smallest radius of the die opening (indicated by either solid arrow in FIG. 35) is taken as the unit length; for Curve C, the smallest diameter (or twice the smallest radius) of the die opening is taken as the unit length. It should be emphasized that this is a pure convention for facilitating the plotting of the curves, and it in no way distorts the final shape or dimensions of the die.

Curves A and B of FIG. 35 belong to Class II, for the reasons discussed above. They are both chosen from the family of curves given by Equation 13a. However, for them to provide good cohesion between as great an area of their segments as is compatible with not having the inner face corners of the segments too pointed or too much in line with the work forces radiating out from the center of the die, they each must have a different polar angle S through which they sweep before ending at the periphery of the die nib. In addition, the

greater the breadth of the die nib wall, the larger S can be chosen (see Equation 14a and b and accompanying text). For this example, the breadth of the die nib wall is taken as equal to the smallest diameter of the die opening (indicated by the solid arrows in FIG. 35). For Curve A, S is chosen at 1.74533 radians (or 100°); for B, $S=0.69813$ radians (or 40°).

Since the midpoint of the straight edge instead of the center of the die opening falls on the origin of the graph in this example, the T of Equation 14a represents here $r_s=1$, where $r_s=2/\cos 10^\circ=2.03$ for Curve A, and $r_s=4$ for Curve B.

One now solves for Alpha in Equation 14a. For Curve A, Alpha= $67^\circ 54'$; for B, Alpha= $26^\circ 42'$. Alpha still represents here the angle between the radius vector of the equation and the tangent to the curve at $\theta=0^\circ$ (see page 11); but, for the same reason as in the preceding paragraph, it no longer represents the angle between the tangent to the curve and the force vector radiating out from the center of the die opening. In the present case, this would have to be corrected by 45° ; for Curve A, this would give $22^\circ 54'$; for B, $71^\circ 42'$. This in no way affects the graphing of the curves. It is only to check that the cohesion between segments at the inner face of the die is sufficient since by Equation 2, $P=H(\sin \Beta/r)$, where Beta equals the corrected angles just given.

Lastly, one substitutes the values of Alpha for Curves A and B in Equation 13a, and graphs the resulting equations in polar coordinates, as shown in FIG. 35.

As established above, the remaining Curve C belongs to Class III and starts from the midpoint of the longest curved side (see FIG. 35). For convenience in plotting it, the smallest diameter of the die opening is taken as the unit length. Thus $T=1$ here. To facilitate in making the segment, one would like the curve to end at the following outer vertex of the die wall. Thus $S=1.25664$ radians (or 72°).

In order to ease the work stresses at the point the curve starts from the inner face of the die, one chooses $\theta_{max}=5^\circ$. In cases where the work stresses are more severe, θ_{max} should be correspondingly larger.

From Equation 31 one can now determine the n corresponding to $T=1$, $S=1.25664$, and $\theta_{max}=0.087267$ radians (or 5°). This $n_{\theta_{max}}$ turns out to be about 2.01. One substitutes this in Equation 29 to calculate Alpha, which in this case is $40^\circ 4'$. From Equation 25, one finds that the corresponding $K=1.543$.

One substitutes the above values for n and K into Equation 19 to obtain the curve one plots finally in polar coordinates, as illustrated in FIG. 35.

As in the other examples, all subsequent steps for finishing the die nib, shrink rings, and casing follow accepted standard procedures.

Having thus set forth my invention, I claim:

1. A die nib comprising a plurality of segments fixed in position, said segments having mutually abutting surfaces, said surfaces intersecting a transverse plane in identical curvilinear lines, whereby each segment comprises one convex side surface and one concave side surface with a concave surface of one segment abutting a convex surface of an adjacent segment, said segments defining an inner opening of a desired shape, the configuration of said curvilinear lines determining a desired distribution of cohesive pressures resulting from working forces, each curvilinear line being defined by

the equation $r=f(\theta)$, where r is a radial vector and f is a function of θ , where θ is the polar angle between a reference line passing through the center of said opening and the radial vector.

2. A stationary segmental die as set forth in claim 1, in which the cohesive pressures between segments increase over a determined initial range, $0 \leq \theta < \theta_{max}$, of the transversal faces of the segments, and in which the cross-sectional curves of the transversal faces,

$$r=f(\theta),$$

satisfy in the above range the following inequality

$$f(\theta)+f'(\theta) < 0,$$

and approximate, over a determined initial range, $0 \leq \theta < \theta_{max}$, the cross-sectional curves of the transversal faces given by the polar equation

$$r=f(\theta)=K[(1/k)^n+\theta]^{1/n}$$

where K and n are positive constants satisfying the inequality

$$K > (n^2/n-1)^{1/2n}.$$

3. The stationary die nib of claim 1 wherein the equation $r=f(\theta)$ is equal to $\text{Sin}(\theta+\alpha)/\text{Sin} \alpha$ and wherein the equation is a polar equation for a cross-sectional curve of the transversal face of each die nib and α is the initial angle the tangent to the curve makes with the horizontal and is from above 0° to less than 90° and the maximum breadth of the effective portion of the die nib is determined from the expression $\text{Csc} \alpha - 1$ and the cohesive pressure between segments is represented by the symbol P and is expressed by the formula

$$P=H/\sqrt{(F'(\theta))^2+(F(\theta))^2}$$

where H is a proportionality factor experimentally determined to establish cohesive pressure P , and the expression $(f'(\theta)^2+f(\theta))^2$ is a constant and wherein the cohesive pressure P between segments is equal along an effective portion of each completely abutting interface of the die nib segments and wherein each θ referred to above is the same as in $r=f(\theta)$ and is the polar angle between the horizontal line and the radial vector r .

4. The stationary segmental die nib of claim 1 wherein the equation $r=f(\theta)$ is derived from the inequality of $2f'(\theta)[f'(\theta)+f(\theta)] > 0$ and wherein the equation is a polar equation for the cross-sectional curve of the transversal face of the segment and wherein the initial angle of the tangent of the curve makes with the horizontal is about from 0° to less than 90° and the maximum breadth of the effective portion of the die nib for logarithmic spirals is determined by $e^{S \cot \alpha} - 1$ where S , a restricted θ , is the polar angle in radians the segmental curve sweeps through before ending at the periphery of the die nib and the cohesive pressure P between die nib segments is expressed by the formula

$$P=H/\sqrt{[f'(\theta)]^2+[f(\theta)]^2}$$

where H is a proportionality factor, the expression $[f'(\theta)]^2+[f(\theta)]^2$ is an increasing function of θ for an effective portion of the cross-sectional curve of the transversal face of the die nib segments.

5. The stationary segmental die nib of claim 1 wherein $r=f(\theta)$ is the generic polar equation for the

cross-sectional curve of the transversal face of the segment, the initial angle α of the tangent of the curve makes with the horizontal is from above 0° to less than 90° and the maximum breadth T_{max} of the die nib is determined by the expression $T_{max}=K(\sqrt{n-1}/n)^{1/n}-1$ where K and n are independent constants satisfying the inequality $K > (n^2/n-1)^{1/2n}$ and the cohesive pressure P between die segments is expressed by the formula

$$P=H/\sqrt{[f'(\theta)]^2+[f(\theta)]^2}$$

where H is a proportionality factor and the cohesive pressure between segments is increased over its effective portion a determined initial range of $0 \leq \theta < \theta_{max}$ of the transversal segmental curves starting from the inner face of the die opening and $[f'(\theta)]^2+[f(\theta)]^2$ is a decreasing function of θ for $0 \leq \theta < \theta_{max}$.

6. The stationary die nib of claim 4 wherein $r=f(\theta)$ is equal to $\theta \cot \alpha$.

7. The segmental die nib of claim 5 wherein $r=f(\theta)$ is equal to $K[(1/k)^n+\theta]^{1/n}$ where K and n are independent positive constants satisfying the inequality of $K > (n^2/n-1)^{1/2n}$.

8. A die nib as claimed in claim 1, wherein said curvilinear lines extend in counterclockwise directions viewing from the top of said die nib.

9. A stationary segmental die as set forth in claim 1, in which the cohesive pressure between segments, expressed by the formula:

$$P=H/\sqrt{[f'(\theta)]^2+[f(\theta)]^2}$$

where H is the factor of proportionality experimentally determined and $r=f(\theta)$ is the generic polar equation for the cross-sectional curve of the transversal face of the segment, is determined, in conjunction with operative conditions, by choice of the cross-sectional curves of the transversal faces of the segments from the group selected from:

- where the cohesive pressures between segments may be equal along the entire interface of the segments and $[f'(\theta)]^2+[f(\theta)]^2$ is a constant;
- where the cohesive pressures between segments may be greater toward the die opening than toward the periphery of the die nib and $[f'(\theta)]^2+[f(\theta)]^2$ is an increasing function of θ ;
- where the cohesive pressures between segments may be made to increase over a determined initial range $0 \leq \theta < \theta_{max}$ of the segmental curve starting from the inner face of the die opening and $[f'(\theta)]^2+[f(\theta)]^2$ is the decreasing function of θ for $0 \leq \theta < \theta_{max}$;
- where the cohesive pressures between segments may be further maximized at the inner face by reflecting the counter clockwise curves of (a), (b), and (c), and wherein α is the initial angle the curve makes with the horizontal, as indicated in the below formula, having its chosen limits from above 0° to less than 90° ; and the maximum breadth of the die nib wall T_{max} for (a) is $\text{Csc} \alpha - 1$; T_{max} for logarithmic spirals in (b) is $e^{S \cot \alpha} - 1$; and T_{max} in (c) is $([n \alpha - S]/n \alpha - 1 + 1)^{1/n \alpha} - 1$.
